CUTTER FOR DREDGES

Laurence T. Gaylord, Upper Montclair, N. J.

Application August 5, 1933, Serial No. 683,743

8 Claims. (Cl. 37—67)

This invention relates to cutters used in dredging operations, and particularly to an improved type of cutter adapted to work efficiently in the beds of rivers, harbors or other bodies of water in which pockets of gas are encountered beneath the surface of the said beds.

During the carrying-on of dredging operations, by means of hydraulic dredges, difficulty is sometimes experienced in maintaining the suction in the pipe through which the material dislodged by the cutter is lifted by the pump, which difficulty arises from the presence of gas in the suction pipe. Such gas is apparently produced by the decay of the vegetable matter that has been covered by the mud and silt of the river bottom and it collects in pockets in the beds of streams or rivers. Where those beds are of non-porous nature or composition, the gas is prevented from escaping as it forms, and consequently, it collects in pockets. When in the course of hydraulic dredging, the cutter of the dredge breaks through the wall of earth surrounding the gas, the latter is released and is drawn into the suction pipe of the dredge. This breaks the suction and causes a stoppage in the dredging operations until the pump can be primed again.

This invention resides in a cutter which is so formed and proportioned as to substantially prevent the entrance of gas into the suction pipe after the release of the gas from the pocket by the cutting away of the bank of the river-bed during the movement of the cutter across said bank.

This invention will be clearly understood by reading the following description in connection with the drawing of which Figure 1 shows in perspective one form of a cutter embodying my invention and Figs. 2, 3 and 4, which are drawn to different scales, represent details of the cutter blades and of their connection to the spider of the cutter.

In Fig. 1, 1, 2 and 3 represent three blades of a six-bladed cutter and 4, 5 and 6 represent the remaining blades thereof. Each blade is bolted, riveted or otherwise suitably fastened to the pads designated 11 which form an integral part of the arms of the spider. These pads are the rectangularly formed ends of the arms of the spider to which the blades are fastened, usually by bolts or rivets. As will be apparent from Fig. 1, the blades 1, 2 and 3 are substantially longer than blades 4, 5 and 6, and are fastened by riveting or other suitable means to a ring 7 which serves to strengthen the cutter structure. An

idea of the proportions of the long blades may be obtained from Fig. 2 which is a plan of the blade on the slope of the blade pad, warping being disregarded. The length of the blade there shown is approximately 7 feet 4 inches. The width of the blade at the rear, marked D—D, is 15 $\frac{3}{4}$ inches and at the front, marked G—G, 11 inches. A cross-section of the blade is shown in Fig. 3 which is on the line B—B of Fig. 2. The nature and extent of the warping of a blade, such as that shown in Fig. 2, is clearly shown in Fig. 4, the various sections of which correspond with those of Fig. 2 having similar designations. The dotted line X—X of Fig. 2 represents approximately the front end of one of the shorter blades 4, 5 and 6. The difference in length of the long and short blades is approximately 3 feet, although this dimension, as well as the dimensions of other parts may vary from those mentioned without departing from the scope of my invention.

The mode of connecting the cutter to its shaft, and the relative positions of the cutter and the mouth of the suction pipe are clearly shown in Fig. 1 in which the apparatus that is behind the parts of the cutter is represented by dotted lines. As will be seen, the hub 8 of the spider is connected to the shaft 9 in the usual manner, and the mouth 10 of the suction pipe is located a short distance back of the arms of the spider.

The manner in which my improved type of cutter operates to accomplish the purpose set forth hereinbefore is as follows. When the cutter is brought into contact with the bank of the material to be dredged, the forward ends of the long blades 1, 2 and 3 begin to cut away the bank and gradually penetrate until the shorter blades make contact with and begin to cut into the bank. If, during the course of dredging, pockets of gas are encountered they will be released by the penetration of the walls of the longer blades. The gas will rise to the surface of the stream instead of being drawn into the suction pipe, which result frequently occurred when gas was encountered during dredging operations in which the conventional cutter having short blades was employed. Consequently, by using a cutter of the type hereinbefore described it is practicable to carry on dredging operations in the bed of a stream containing gas, with substantially no interruptions of those operations due to a breakage of the suction by gas getting into the suction pipe.

On the other hand, the material that is cut by the shorter blades 4, 5 and 6 as well as by

the rear ends of the longer blades 1, 2 and 3 will be drawn freely into the suction pipe, through the mouth 10.

While the invention has been disclosed as embodied in a particular form, it is to be understood that it is not so limited but is capable of embodiment in other and different forms without departing from the spirit and scope of the appended claims.

10. What is claimed is:

1. A dredge-cutter comprising a spider having a plurality of arms, and a plurality of blades each attached to one of said arms, certain of said blades being longer than the others, and extending forwardly thereof to such distance that the material stirred up by said extended portions will be outside the effective suction range.
2. A dredge-cutter characterized by having means extending beyond the cutting zone of said cutter to penetrate the material about to be cut and to release the occluded gases at a point well beyond the effective suction range.
3. A dredge-cutter comprising a spider having a plurality of arms and a plurality of blades each attached to one of said arms, certain of said blades extending forward a greater distance than others, the said forward extending blades being securely fastened near the front ends thereof and the forward extensions being of such length as to release the occluded gases beyond the suction range.
4. A dredge-cutter comprising a spider having a plurality of arms, and a plurality of blades each attached to one of said arms, certain of said blades being longer than those adjacent thereto the longer blades extending forwardly beyond the effective suction range.
5. A dredge-cutter comprising a spider having a plurality of arms, and a plurality of blades

each attached to one of said arms, the adjacent blades being of different lengths, and every other blade being of substantially the same length the longer of said blades extending forwardly beyond the effective suction range.

6. In dredging apparatus for use in places containing pockets of gas, the combination with a cutter having a plurality of blades, of means for rotating the said blades, and a suction pipe having its mouth adjacent to the rear of said blades, certain of said blades extending forward to such extent that the gas released by the breaking away of the walls of the pockets by the forwardly extending blades will not be drawn to substantial extent into said suction pipe.

7. A dredge-cutter comprising a spider having a hub and arms attached to said hub, each arm having a pad connected to the end thereof, a plurality of blades each attached to one of said pads, the said blades being of such length as to extend a substantial distance in front of said arms and certain of said arms extending beyond the forward limits of the others to such extent that the material stirred by the said extensions will be beyond the effective suction range.

8. In a hydraulic dredging system the combination with a cutter spider having a plurality of arms, of a suction pipe having its mouth in close proximity to the back of the arms of said cutter, and a plurality of blades each attached to one of said arms, all of the said blades being of such length as to extend a substantial distance beyond the front of said arms and certain of said blades extending beyond the forward limits of the others to such extent that the material stirred by the forward extensions will be beyond the effective suction range.

LAURENCE T. GAYLORD.
